UNITED STATES PATENT OFFICE.

ELWOOD C. PHILLIPS, OF CHICAGO, ILLINOIS.

DESIGN FOR A VEHICLE-WHEEL.

SPECIFICATION forming part of Design No. 31,684, dated October 17, 1899.

Application filed August 21, 1899. Serial No. 728,017. Term of patent 7 years.

To all whom it may concern:

Be it known that I, ELWOOD C. PHILLIPS, a citizen of the United States, residing at Chicago, in the county of Cook and State of Illinois, have invented and produced a new and original Design for Vehicle-Wheels, (Case B;) and I do declare the following to be a full, clear, and exact description of the same, reference being had to the accompanying drawings, forming a part of this specification, in which—

Figure 1 is a view one-half in section and one-half in end elevation, and Fig. 2 a side elevation.

15 This invention relates to a design for wheels for buggies and other light vehicles; and my said design consists in the structural configuration hereinafter described and illustrated in the drawings.

20 Referring to the drawings, 1 represents the wheel-tire, the outer portion of which is cylindrical in cross-section, while the inner por-

tion 2 is rectangular in cross-section and integrally connected with the outer portion by a central web 3, so as to leave at each side of 25 the tire a concentric annular recess.

4 is the wheel-hub, and 6 the felly, connected together by the series of radial spokes 5.

7 are a pair of annular plates or rings arranged at opposite sides of the rim or felly 6 30 and formed with inturned annular beads or flanges 8 on their outer edges to engage in the respective annular recesses in the sides of the tire.

I claim—

35 The design for a vehicle-wheel, as herein shown and described.

In testimony whereof witness my hand this 14th day of August, 1899.

ELWOOD C. PHILLIPS.

In presence of—

ROBERT BURNS,
M. H. HOLMES.
